UNITED STATES PATENT OFFICE.

ABRAHAM SIMON, OF NEW YORK, N. Y.

DESIGN FOR A GARMENT.

SPECIFICATION forming part of Design No. 18,925, dated May 22, 1883.

Application filed April 2, 1883. Term of patent 34 years.

To all whom it may concern:

Be it known that I, ABRAHAM SIMON, of the city, county, and State of New York, have invented and produced a new and original Design for Garments, of which the following is a full, clear, and exact description.

Reference is to be had to the accompanying drawings, forming part of this specification, in which similar letters of reference indicate corresponding parts in both the figures.

Figure 1 is a front perspective view of a boy's coat, showing my design applied thereto. Fig. 2 is a rear elevation of the same.

The leading feature of my design consists in folded pieces of the fabric placed in square or diamond-shaped apertures in the garment.

A is a garment in which are formed square

or diamond-shaped apertures B, in which are placed folded pieces C of the fabric, giving a very pleasing, attractive, and ornamental appearance to the said garment. In the case of coats these ornaments B C are placed in two rows upon the front and back of the garment, upon the lower parts of the sleeves, and upon the collar.

25

I claim—

The design for a garment herein shown and described, the same consisting of the folded pieces of fabric placed in square or diamond-shaped apertures in the said garment.

ABRAHAM SIMON.
